UNITED STATES PATENT OFFICE.

CECILIA BESSE, OF WATERTOWN, MASSACHUSETTS.

HEEL-PROTECTOR FOR RUBBER SHOES.

1,187,489.

Specification of Letters Patent. Patented June 20, 1916.

Application filed October 19, 1915. Serial No. 56,786.

To all whom it may concern:

Be it known that I, CECILIA BESSE, a citizen of the United States, and resident of Watertown, in the county of Middlesex and State of Massachusetts, have invented an Improvement in Heel-Protectors for Rubber Shoes, of which the following description, in connection with the accompanying drawings, is a specification, like letters on the drawings representing like parts.

10 My present invention is an improved rubber overshoe and heel protector therefor, the protector being specially adapted for application to a rubber shoe or overshoe.

15 In the use of rubber shoes, particularly rubber overshoes or "rubbers," the greatest wear comes upon the heel portion, as is well known, and as soon as the rubber in the heel is worn through, the overshoe no longer 20 is waterproof and must be discarded.

25 My invention has, for its object, the elimination of this difficulty in rubber shoes, particularly overshoes, and I have devised a metallic heel protector, especially adapted for use on a rubber overshoe to prevent the wearing down at the heel, and yet which may be easily attached to the overshoe without forming holes through the rubber which would endanger the waterproofness of such 30 overshoe.

The combination of the rubber shoe with a heel protector is peculiarly difficult, since any rivets, prongs, or the like through the bottom portion, which might be employed 35 to hold the protector on to the rubber, cannot be used in an overshoe without destroying the waterproof characteristic of the overshoe and rendering same unsatisfactory. My invention overcomes these difficulties and 40 enables a rubber shoe with a firmly secured metallic heel protector to be manufactured, which will not only prevent the wearing out at the heel of the overshoe, but which will be held firmly and securely thereon, and 45 without any openings through the bottom portion of the overshoe nor through the sides, excepting so far above the heel as to be above the ordinary depth of water apt to be encountered by the wearer. I accomplish 50 this object by a novel form of heel protector adapted to fit around the heel portion of a rubber shoe, protecting the edge and bottom of the heel and having a plurality of prongs extending entirely above the tread surface 55 of the heel, where they may be turned in and

clenched upon the counter, well above the ordinary depth of water to which the shoe would be likely to be plunged. I provide the bottom or tread portion of the protector with a plurality of specially formed recesses 60 or openings to fit snugly into and interlock with the tread surface of the rubber heel, which rubber will be forced therein, thus uniting the metallic protector and the rubber of the heel in a firm yet yielding contact. 65 These recesses, furthermore, are preferably so formed to provide a roughened or anti-slipping surface on the exposed tread portion of the metallic heel protector. These recesses, therefore, perform the important 70 function of enabling a firm union with the bottom of the rubber heel to be secured without rivets, nails, prongs, or the like, which would penetrate the rubber and endanger the waterproofness of the same, as well as 75 constituting an anti-slipping and wear-resisting surface.

Referring to the drawings illustrating a preferred embodiment of my heel protector and a rubber shoe equipped therewith, Figure 80 1 is a side view of an overshoe embodying the invention; Fig. 2 is a view partly in longitudinal cross section of the heel portion; Fig. 3 is a cross sectional view on the line 3—3 of Fig. 1; Fig. 4 is a top plan view of the heel 85 protector; and Fig. 5 is a rear elevation of the protector detached from the shoe.

In the drawings, 1 indicates a rubber overshoe of ordinary type, having the rubber sole 2, instep portion 3, and rubber heel 4, in 90 the heel portion also, is the usual counter 5.

My heel protector has the important advantage of being readily applicable to any existing overshoe, no special construction of the rubber shoe being necessary to enable 95 the heel protector to be applied. Such metallic heel protectors will be made of suitable style and sizes to fit a corresponding size and style of rubber shoe, and may also be of appropriate color, *i. e.* black, tan, 100 or the like, to correspond with the color of the overshoe to which it is applied.

The heel protector comprises the bottom plate 6, having an upturned flange 7, which plate and flange are of appropriate size and 105 contour to fit snugly around the heel portion of a rubber shoe. The plate 6 is formed with a plurality of recesses or openings 8 extending from the inner or rubber-engaging surface downwardly, being preferably 110

stamped through the plate 6 and forming a roughened, anti-slipping surface 9 on the outer side of the plate 6. The plate 6 also is provided with upstanding prongs 10, 11, and 12, at opposite edges of the plate 6 and at the rearmost end, substantially as indicated in the drawings. These prongs extend upwardly for a considerable length, preferably as high as the counter 5, where they may be bent inwardly over or through the counter and clenched therein, as clearly shown in Figs. 2 and 3. These points being sufficiently high to prevent any danger of leakage during the ordinary usage to which the rubber may be put. The protector and rubber are united with sufficient firm pressure to force the plate 6 somewhat into the surface of the rubber heel 4, embedding the bottom of the rubber directly into the recesses 8 and also embedding the plate 6 into the rubber heel, so that the edge of such plate as it extends across the heel will be substantially flush therewith, as indicated at 13, Figs. 1 and 2.

The advantages of a rubber heel provided with a metallic protector, which protector is firmly attached and interlocked with the tread surface of the heel without any rivets or the like penetrating the rubber, will be readily appreciated. The wear-resisting effect obtained by the metallic heel

and the anti-slipping tread surface of the metallic portion are specially important advantages.

The protector can be applied to the existing overshoes with a minimum of time and labor, and without special skill or tools.

Having described my invention, what I claim as new and desire to secure by Letters Patent is:

A rubber shoe, having in combination with the rearmost portion of the heel, a metallic protector, adapted to fit about the lower back corner of the tread surface and having a large number of depressions arranged to constitute embedding and suction members on the tread of the rubber shoe to provide a firm union of the protector and the rubber shoe, said suction members consisting in anti-slipping projections on the outer tread surface of the protector, and a plurality of prongs extending from the tread portion of the protector and clenched within the rubber shoe at a point remote from the tread surface.

In testimony whereof, I have signed my name to this specification, in the presence of two subscribing witnesses.

CECILIA BESSE.
